UNITED STATES PATENT OFFICE.

BENEDICT B. LEDERER, OF PROVIDENCE, RHODE ISLAND.

ORNAMENTAL CHAIN.

SPECIFICATION forming part of Letters Patent No. 258,084, dated May 16, 1882.

Application filed January 23, 1882. (No model.)

To all whom it may concern:

Be it known that I, BENEDICT B. LEDERER, of the city and county of Providence, and State of Rhode Island, have invented a new and useful Improvement in Ornamental Chains; and I hereby declare that the following is a full, clear, and exact description of the same, reference being had to the accompanying drawings, forming part of this specification.

10 This invention has reference to an improvement in the construction of chains, and may also be applied to chain-bracelets.

The invention consists in the peculiar construction of such chains by cutting slits into 15 tubular wire, cutting the same into lengths equal to the width of the chain, and securing the same together to form a chain or bracelet, as will be more fully set forth hereinafter.

Figure 1 is a view of my improved chain. 20 Fig. 2 is a perspective view of one of the lengths of tubular wire forming part of my improved chain. Fig. 3 is a perspective view of one of the connecting-rings. Fig. 4 is a view and section of a piece of tubular wire partly cut to 25 form the parts of the chain. Fig. 5 is a sectional view, showing the manner of connecting the links. Fig. 6 is a perspective view, showing a chain made entirely of tubular links cut into the sides of the tubes and secured together 30 by wires.

What are known in the art as "roller-chains" have long been made out of rings secured together by weaving continuous wires through 35 the rings and by uniting such rings by means of wires or staples. Such chains have been used as long chains, fob-chains, and also for chain-bracelets. By my present invention chains similar to these roller-chains can be made much stronger and cheaper than in the 40 old way.

In the drawings, A is a chain, B a slide, C an ornamented end piece, and D a fringe. The chain is made up of pieces of tubular wire, into the sides of which slits are cut. E is such a 45 piece of tubular wire having the slits cut into the flattened sides thereof. F F are the connecting-rings by which the tubular pieces E E are connected, the rings F F being passed through the slits and around the uncut portion 50 of the tube.

In the modification shown in Fig. 6, which consists of a number of tubular pieces, E E, having notches cut into their sides, so that the metal of one set will enter the slots in the other, they are secured by pieces of wire inserted between the two links, so as to lock them together. The wires may be secured by solder, or by bending the ends inward. 55

I am aware that chain-links have been made out of tubular wire ornamented by cutting 60 notches into the sides or edges thereof; but such links were secured together on their ends and the axis of the tube was on a line with the line of the chain. Such chains had no resemblance to and could not be used in place of 65 roller-chains.

I am aware that rings placed side by side, but some distance apart, and attached together by means of wire soldered thereto, said wire serving as supports for the connecting-links, are 70 old.

I am also aware that boxes having the top and bottom removed and the edges of the front and rear parts notched to hold connecting-links are old, and these I do not claim, as my 75 device is simply a tube having notches cut therein to receive the connecting-links. By making the chains in this manner I dispense with all soldering of sections or rings and with staples and wire, thus making a cheaper and 80 more serviceable chain.

Having thus described my invention, I claim as new and desire to secure by Letters Patent—

1. As a new article of manufacture, a chain made up in part or whole of pieces of tube, having notches cut into the sides thereof, placed transversely to the chain and secured together along the sides of the tubes, as described. 85

2. In an ornamental chain, the combination, with the tubular links E E, placed transversely 90 to the line of the chain and having notches cut into the sides thereof, of the rings F F, arranged to connect the tubular links together, as described.

BENEDICT B. LEDERER.
